UNITED STATES PATENT OFFICE.

ELVINA ROOT, OF COQUILLE, OREGON.

COFFEE OR TEA POT.

SPECIFICATION forming part of Letters Patent No. 654,675, dated July 31, 1900.

Application filed October 21, 1899. Serial No. 734,351. (No model.)

To all whom it may concern:

Be it known that I, ELVINA ROOT, residing at Coquille, in the county of Coos and State of Oregon, have invented Improvements in 5 Coffee or Tea Pots, of which the following is a specification.

My invention relates to strainers for coffee or tea pots and like vessels.

One embodiment of the invention is illustrated in the accompanying sheet of drawings, in which—

Figure 1 is a view in elevation with parts broken away, showing the strainer in position. Fig. 2 is a horizontal section on the line $x^2 x^2$ of Fig. 1 with the strainer removed. Fig. 3 is a similar view with the strainer in position, and Fig. 4 is a plan view of the strainer detached.

Throughout the several views like numerals of reference indicate like parts.

Referring to the drawings, 1 represents a vessel. In the present instance an ordinary coffee-pot is shown, which is interiorly flanged, as indicated at 2, (see Fig. 2,) and provided 25 with a series of lugs 3 3 3. The lugs extend upwardly from the flange and have their ends bent over to serve as engaging hooks for the strainer.

4 represents the strainer, which consists of 30 a flat ring 5, provided circumferentially with cam-like enlargements 6 6 6, corresponding in number with the lugs or hooks upon the flange of the pot. To the ring or annular base the strainer proper, 7, is suitably attached—as, for example, by the wires 8 8, 35 which are arched over the semispherical gauze

and bent up centrally thereof to form a knob 9, by means of which the strainer may be manipulated.

In use the strainer is placed within the vessel so that it rests upon the flange and is locked in position by turning it until the cams or peripheral enlargements find under the lugs or hooks. Its removal may be effected by reversing the operation above described.

The advantages of the device consist in its extreme simplicity, cheapness, and effectiveness in use.

It is evident that various changes could be made in the details of construction without departing from the spirit and scope of my invention.

Having thus fully described the invention, I claim—

The combination with the vessel 1, provided 55 interiorly with the flange 2, having secured upon its upper side a series of undercut lugs 3, of a strainer, comprising a ring-base 5 cut away circumferentially to form clamp members 6, adapted to coöperate with and lock 60 under the lugs 3, an approximately-hemispherical gauze body 7, upon the ring and a series of wire strands 8, securing the gauze by extending upward from the ring 2, over the gauze and terminating centrally of the 65 latter in the form of a handle 9, as specified.

In testimony whereof I affix my signature in the presence of two witnesses.

ELVINA ROOT.
